UNITED STATES PATENT OFFICE

OKEY E. NICHOLS, OF CHARLESTON, WEST VIRGINIA, ASSIGNOR, BY MESNE ASSIGNMENTS, TO SAFETY MANUFACTURING COMPANY, OF CHARLESTON, WEST VIRGINIA, A CORPORATION OF WEST VIRGINIA

TROLLEY WIRE GUARD SUPPORT

Application filed December 23, 1931. Serial No. 582,826.

The invention relates to a new and improved support to facilitate the mounting of guard strips at opposite sides of mine trolley wires, wherever the wire passes over a track or other passageway.

The principal object of the invention is to provide a unique support of sectional construction which may be quickly and easily applied to a conventional trolley wire insulator.

Another object is to provide a novel structure in which the upper ends of hangers for the guards, are provided with means for holding clamp sections relatively assembled around the insulator.

A still further object is to provide a construction of exceptionally simple and inexpensive nature, yet one which will be efficient and desirable from numerous standpoints.

With the foregoing in view, the invention resides in the novel subject matter herein-after described and claimed, description being accomplished by reference to the accompanying drawing.

Fig. 1 is a perspective view partly broken away and in section, showing two of the guard supports applied.

Fig. 2 is a vertical transverse sectional view on line 2—2 of Fig. 1.

Fig. 3 is an enlarged perspective view of one of the guard supports.

In the drawing above briefly described, W denotes a portion of a conventional trolley wire for a mine, I refers to insulators which support said trolley wire, G denotes the guards at opposite sides of the wire, and S has reference to supports for the guards G, constructed in accordance with the present invention. Two or more of these supports are used for each pair of guards, and as they are all of the same construction, a description of one will suffice.

The support S comprises a clamp having a central yoke portion to surround the insulator I, two arm portions projecting in opposite directions from said yoke portion, and two hangers H depending from said arm portions and adapted to support the guards G. In the preferred construction,

the clamp is formed from two horizontally elongated bar-like sections 10 having outwardly bowed central portions 11 to jointly embrace the insulator I, the portions of said sections 10 which project from the bowed portions 11, being disposed side by side and substantially in contact with each other. These ends of the sections 10 are snugly received in links 12 forming the upper portions of the hangers H, so that the two clamp sections are held in assembled relation, engaged with the insulator I. Preferably, the upper edges of the clamp sections 10 are formed with notches 13 which receive the links 12 and the portions 14 at the outer sides of these notches, constitute lugs which prevent said links 12 from accidentally shifting from the clamp.

Each link 12 is preferably formed by a metal stamping as shown, being formed with an upper relatively large opening 15 and a lower smaller opening 16. The openings 15 of the two links 12, receive the ends of the clamp sections 10, and the smaller openings 16 facilitate connection of the lower hanger sections 17, with the upper sections or links 12. Each section 17 may well be formed by a length of heavy insulated wire anchored at one end in the opening 16 and bent to surround the guard G.

In applying the clamp to the insulator I, the two clamp sections are positioned so that their bowed portions 11 jointly surround said insulator, the link 12 of one of the hangers H is engaged with the clamp sections at one end of the latter, the other ends of these clamp sections are then pressed together, and the link 12 of the other hanger is then engaged with them. The clamp is thus tightly held upon the insulator, and the hangers H may be readily connected with the guards G, by bending them around said guards and fastening their ends, as shown.

The guards, when supported by a number of the supports herein disclosed, serve effectively to prevent the heads of persons or animals walking under them, from coming in contact with the trolley wire W and it

will be understood that said guards may be mounted wherever advisable.

The details disclosed may be considered as preferred, but within the scope of the invention as claimed, numerous variations may be made.

I claim:—

1. A trolley wire guard support comprising a contractible clamp to surround a trolley wire insulator, and guard-supporting hangers having links at their upper ends for holding said clamp contracted.
- 10 2. A trolley wire guard support comprising a clamp to surround a trolley wire insulator, said clamp being divided into two sections adapted to jointly embrace the insulator, and guard supporting hangers having links at their upper ends for holding said clamp sections in assembled relation.
- 20 3. A trolley wire guard support comprising two elongated clamp sections having outwardly bowed portions between their ends adapted to jointly surround a trolley wire insulator, and guard-supporting hangers having links at their upper ends receiving the ends of said clamp sections to hold the latter assembled.
- 25 4. A trolley wire guard support comprising two elongated clamp sections having outwardly bowed portions between their ends adapted to jointly surround a trolley wire insulator, and guard-supporting hangers having links at their upper ends receiving the ends of said clamp sections to hold the latter assembled, said ends of said clamp sections being provided with lugs preventing accidental movement of said links therefrom.

In testimony whereof I affix my signature.

OKEY E. NICHOLS.
